UNITED STATES PATENT OFFICE.

NEWTON E. FERRELL, OF WEST FINLEY, PENNSYLVANIA.

CHURN.

SPECIFICATION forming part of Letters Patent No. 597,970, dated January 25, 1898.

Application filed June 10, 1897. Serial No. 640,196. (No model.)

To all whom it may concern:

Be it known that I, NEWTON E. FERRELL, a citizen of the United States, residing at West Finley, in the county of Washington 5 and State of Pennsylvania, have invented new and useful Improvements in Churns, of which the following is a specification.

This invention relates to churns of that class in which the dasher is to have a vertical reciprocation and also an oscillatory or rotary movement, first in one direction and then in the other, thus imparting four motions to the dasher, or a right-and-left and up-and-down movement in spiral circles.

15 In the annexed drawings, Figure 1 is a sectional elevation of my improved churn. Fig. 2 is a partly-sectional view of the socketed and spirally-grooved dasher-shaft. Fig. 3 is a plan of a two-part collar to be loosely 20 mounted on the dasher-shaft and provided with an arm for attachment of a pitman to reciprocate the dasher in a vertical direction. Fig. 4 is a perspective of the churn-dasher.

The churn-body 1 may be of any suitable 25 or usual form, preferably cylindrical. There is mounted on the churn-body a vertically-extended frame 2, that supports at its upper part a nut or bearing 3, the bore of which is spirally ribbed to engage with the spiral 30 grooves 4 of a dasher-shaft 5, Figs. 1 and 2. This dasher-shaft 5 is shouldered or provided with a circumferential groove 6, Fig. 2, in which is mounted a loose collar 7, Fig. 3, that is preferably formed in two parts united 35 by bolts 8 to facilitate fitting the said collar onto or around the shaft.

From one side of the loosely-mounted collar 7 there projects a bearing 9 for attachment of the upper end of a pitman 10, the 40 lower end of which connects with a wrist-pin 11 on a gear-wheel 12, that is mounted in the lower part of the churn-frame. A crank-handle 13, connected with the gear-wheel 12, affords means for rotating said wheel to impart 45 vertical movement to the dasher-rod 5 through the intermediate pitman. In its vertical movement the dasher-rod 5 has also imparted to it a rotary or oscillatory motion, first in one direction and then the other, 50 through the spirally-grooved connection of the said shaft with the nut or bearing 3,

through which the shaft is passed. The loose collar 7 permits the required oscillatory or rotary movement of the dasher-shaft 5 simultaneously with its vertical reciprocation. 55 A nut or a slip-collar 14 is provided on the end of the bearing 9 to hold the end of the pitman 10 onto said bearing.

The gear-wheel 12 meshes with a pinion 15 to drive a shaft on which a fly-wheel 16 is 60 also mounted.

In the lower end of the dasher-rod 5 is a socket 17 to receive the staff 18 of the dasher 19, and a set-screw 20 or other suitable fastening is provided for detachable connection of 65 the said shaft and dasher-staff.

The dasher 19, Fig. 4, comprises crossed bars 21, secured to the lower end of the staff 18 in a horizontal direction and at right angles to each other, and also similar crossed 70 bars 22, secured to the staff at about eight inches, more or less, from its lower end. These lower crossed bars 21 and upper crossed bars 22 afford attachment for diagonally-arranged spindles 23 and 24, that are inclined 75 in opposite directions, as shown, one pair of spindles, 23, being extended, for instance, from the inner or central portion of one lower cross-bar 21 to the outer ends of the corresponding upper cross-bar 22, and the other pair 80 of spindles, 24, being extended from the outer ends of the other lower cross-bar to the central portion of the corresponding upper cross-bar. It will be seen that with the means for imparting to this dasher a vertical reciprocation 85 or up-and-down movement and an oscillation first to the right and then to the left each inclined spindle 23 and 24 will cut a different spiral circle in the milk, so that with the four motions given to the dasher the milk is 90 thoroughly and rapidly agitated in a great variety of directions and the butter is quickly separated. The churn is very easily operated and does its work speedily and effectively, making it possible to churn the milk at 95 a low temperature and preserve the natural color of the butter.

What I claim as my invention is—

In a churn, the combination of the axially-oscillatory and vertically-reciprocating 100 dasher-shaft having an annular groove intermediate the shaft ends and provided with a

spiral groove throughout the upper portion of the shaft, a frame provided at the top with a fixed nut having a spirally-ribbed bore engaging the spiral groove of said shaft to impose oscillation thereto on up-and-down movement of the shaft, a collar loosely mounted in said annular groove of the dasher-shaft, a pitman connected to said loose collar, gearing for driving the pitman, and a dasher de-

tachably connected with said shaft, substantially as described.

In testimony whereof I have hereunto set my hand in presence of two subscribing witnesses.

NEWTON E. FERRELL.
